UNITED STATES PATENT OFFICE

CHARLES SAMUEL FRANKLIN, OF BUCKHURST HILL, ENGLAND, ASSIGNOR TO RADIO CORPORATION OF AMERICA, A CORPORATION OF DELAWARE

DIRECTIONAL ANTENNA

Application filed June 2, 1926, Serial No. 113,123, and in Great Britain June 30, 1925.

This invention relates to directional antenna systems for radio transmission and reception, which are constructed in the form of a line of separate aerials fed through a system of feeders, so that the phases of the currents in all the aerials are maintained substantially constant.

According to this invention an antenna system for the transmission or reception of wireless telegraphy and telephony comprises a plurality of aerials, some of which are coupled or connected directly to the transmitter or receiver, while the others are maintained in correct current phase by radiation or re-15 radiation from the first mentioned aerials.

The object of this invention is to obtain greater efficiency in directional propagation and reception of radio oscillations.

Another object is the excitation of aerials adjacent to the power aerials in the proper phase relationship.

A further object is the excitation of the power aerials in proper phase relation.

Further objects and advantages of my invention will appear as set forth more fully in the accompanying specification and by reference to the drawing, in which one form of the antenna arrangement for carrying out my invention is schematically shown.

In an antenna system in which each aerial is spaced half a wave length from its neighbor on either side, the oscillation voltage induced in any aerial, by radiation from the two adjacent aerials is in correct phase and 30 assists the current impressed upon the said aerial by the feeder coupled to it. The result is that each aerial tends automatically to maintain the correct current phase of the adjacent aerials. It is, therefore, not essential to feed every aerial. Every second or even every third aerial need only be directly fed by the feeders, since each aerial connected to a feeder can energize, by radiation, an aerial on either side of it at a distance of 45 half a wave length. This simplifies the feeding system.

Referring to the drawing aerials 2 and 4, which are energized, are of the type described in my co-pending application, Serial 50 #472,322, filed July 31st, 1925, and each con-

sists of two sections, S_1 , one-half wave-length long, located one above the other, and connected by phase reversing coils A and B. Radiation is null or nearly so from the coils or center half wave length portion of the aerials 55 2 and 4, so that radiation takes place only from the upper and lower sections S_1 of the aerials, as is more fully set forth in my co-pending application referred to above. This result is obtained by concentrating alternate 60 half wave length portions of the wire in a small space to prevent radiation therefrom. In the form of the invention illustrated, the coils A and B connecting the sections S_1 are inductances of a value equivalent to half a 65 wave length of the aerial wire so that while radiation from the parts A and B is substantially null, the portions S_1 , which do radiate, are in phase. The polar curve of the radiation from the antenna will be in a direction at right angles to the aerial and to the plane thereof. The sharpness in elevation of the beam radiated will depend on the number of alternate sections and null points in each vertical aerial.

In this manner, the correct phase of the current in the upper and lower sections S_1 is obtained, and the energy beam radiated is 70 directive in elevation.

Radiation may also be suppressed from alternate half wave length portions by doubling such portions back on themselves instead of forming a coil such as has been illustrated.

Referring again to the drawing, 1, 2, 3, 4 85 and 5, are aerials spaced approximately $\frac{1}{2}$ wave length apart. The sections S_1 of the aerials 2 and 4 are connected by coils A and B and are energized from the transmitter (not shown) through a symmetrically 90 branched feeding system F and aerial transformers T_1 and T_2 . The aerials 1, 3 and 5 are not connected to the transmitter and do not contain phasing coils between the sections S_2 but they are energized by radiation 95 from the power antennas 2 and 4. The aerials 1, 3 and 5 reradiate or reflect the energy radiated from aerials 2 and 4.

It will readily be seen that if the spacing between adjacent aerials is exactly $\frac{1}{2}$ wave 100

length, the separate sections S_2 will be maintained in phase. In practice it is not necessary that this spacing be exactly $\frac{1}{2}$ wave length, as by small adjustment of the tune 5 of the sections S_2 of the aerials 1, 3 and 5, the phase of the currents induced therein can be controlled.

I have found that in an antenna system, constructed as above described, all the aerials 10 can be maintained in phase, and that the said system functions substantially as if all the aerials were fed directly from a transmitter by a more complicated system of branched feeders.

15 In general, the smaller the spacing between the aerials and the larger the number employed, the nearer the system approaches to an ideal current sheet, while if the spacing is made of the order of two or more half wave 20 lengths, instead of a single half wave length, the directional properties of the system in azimuth are to a large extent lost.

This invention is likewise applicable to the 25 reception of radio telegraphy and telephony. In this case, the currents induced in the aerials 1, 3 and 5, from the incoming signal wave, effect by re-radiation the currents induced in the aerials 2 and 4 to a degree dependent upon the direction of origin.

30 Having thus described my invention, what I claim is:

1. In a directive antenna system, the combination of a plurality of aerials coupled to a single work circuit, and a plurality of sectional disconnected aerials operated by said first mentioned aerials by radiation and maintained in correct current phase by being symmetrically spaced therefrom, at a distance of substantially $\frac{1}{2}$ wave length.

40 2. In a directive antenna system, the combination of a plurality of aerials coupled to a work circuit, a plurality of disconnected aerials operated by said first mentioned aerials and maintained in proper current phase by being spaced therefrom a distance equal to substantially $\frac{1}{2}$ wave length, said latter mentioned aerials each comprising a plurality of electrically insulated sections placed one above the other.

50 3. In a directive antenna system, the combination of a plurality of aerials coupled to a work circuit, a plurality of disconnected aerials operated by said first mentioned aerials and maintained in proper current phase by being spaced therefrom a distance equal to substantially $\frac{1}{2}$ wave length, said first mentioned aerials comprising a plurality of sections substantially $\frac{1}{2}$ wave length in length and connected by a relatively concentrated inductance of the value of $\frac{1}{2}$ wave length, and said last mentioned aerials comprising a plurality of electrically insulated sections approximately $\frac{1}{2}$ wave in length.

65 4. A directive antenna system comprising a plurality of sectional reflectors, a plurality

of radiators alternated with said reflectors and symmetrically spaced relative thereto, and a single means to energize said radiators in phase.

5. A directive antenna system comprising 70 a plurality of reflectors composed of upper and lower sections insulated from each other, means for maintaining said reflector sections in correct phase relationship comprising a plurality of radiators symmetrically alternately spaced with relation to said reflectors, and a common exciting means for said radiators.

6. A directive antenna system comprising 80 a plurality of spaced radiators, inductances in each radiator adapted to suppress radiation from alternate half wave lengths thereof, a plurality of reflectors composed of upper and lower sections alternately and symmetrically spaced relative to said radiators, and means for maintaining said reflectors and radiators in phase including a common means for exciting all of said radiators.

7. A broadside directive antenna system comprising a plurality of aerials lying in a 90 single plane, some of which are maintained in phase by being coupled to a common work circuit and energized thereby, others of which are maintained in correct phase relationship by radiation from the first mentioned 95 energized aerials.

8. A broadside directional antenna system for the transmission or reception of short waves comprising a plurality of aerials, lying in a single plane, some of which comprise a 100 plurality of radiating sections coupled by phase reversing nonradiating portions, and are maintained in phase by being symmetrically coupled to a common work circuit, others of which are composed of a plurality of electrically insulated sections and are maintained in correct phase relationship by means of their symmetrical spacing relative to the first mentioned aerials.

9. A broadside directional antenna system 110 for the transmission or reception of short waves comprising a plurality of upright parallel aerials lying in a single plane, alternate aerials having a plurality of half wave length sections coupled by substantially non 115 radiating portions an electrical half wave in length, a symmetrically branched transmission line system for coupling said aerials to a common work circuit, the other alternate aerials comprising a plurality of electrically 120 insulated half wave length sections, said aerials being spaced a half wave length apart to operate cophasally.

CHARLES SAMUEL FRANKLIN.
